HAIR CLIPPER

Bogota Strezzoff, Minneapolis, Minn.

Application October 7, 1936, Serial No. 104,392

4 Claims. (Cl. 30—208)

This invention relates to hair clipping devices and more particularly to that type of hair clippers, wherein there is a stationary cutting member with cutting teeth which co-operate with similar teeth on a movable cutting member.

It is an object of my invention to provide a hair clipping device of simple construction wherein none of the assembling and tensioning bolts extend upwardly through the bottom of the lower blade member, thus eliminating the necessity for apertures in the lower face of said blade which might catch the ends of the hair being clipped with the resulting discomfort occasioned by such catching and pulling.

It is a further object of my invention to provide a clipper construction which will permit convenient removal of the cutting blades for sterilizing or sharpening.

It is a still further object of my invention to provide such a construction which is adaptable to either manually operated hair clippers or power-driven clippers.

These and other objects and advantages of my invention will be fully set forth in the following description made in connection with the accompanying drawings, in which like reference characters refer to like parts throughout the similar views, and, in which—

Fig. 1 is a perspective view of one embodiment of my device;

Fig. 2 is a slightly enlarged top plan view with the cap plate broken away;

Fig. 3 is a vertical section on the line 3—3 of Fig. 2;

Fig. 4 is a vertical section on the line 4—4 of Fig. 3;

Fig. 5 is a plan view of the movable cutting blade;

Fig. 6 is a plan view of the stationary cutting blade;

Fig. 7 is a section taken on the line 7—7 of Fig. 2;

Fig. 8 shows a modified form in plan view with a back plate secured for use with power operating means;

Fig. 9 is a vertical section taken on the line 9—9 of Fig. 8;

Fig. 10 is a transverse section taken on the line 10—10 of Fig. 8;

Fig. 11 is a transverse section taken on the line 11—11 of Fig. 8;

Fig. 12 is a transverse section taken on the line 12—12 of Fig. 8;

Fig. 13 is a bottom plan of the stationary cutting blade; and

Fig. 14 is a combined side elevation and vertical section of the structure shown in Fig. 8 as applied to hand-operated clippers, the handles being broken away.

Referring more particularly to Figs. 1 through 7, I provide a stationary supporting arm or handle 15, which terminates at its lower end in an integral substantially cylindrical housing 16 which contains a helical spring 17 adapted to work against a shoulder 18 near the lower end of the movable handle 19. The housing 16 has a forward longitudinal extension 20 provided with a horizontal transverse slot 21. The lower flange formed by said slot has an outer edge which extends downwardly and backwardly, as shown at 22, for a reason to be described later on.

A stationary cutting blade 23 is formed with a horizontal extension 24 on its rear edge which is adapted to fit into the slot 21 in the extension 20 of the cylindrical housing 16. The forward edge of the stationary cutting blade is provided with a series of cutting teeth 25, which are of the conventional type.

A movable cutting blade 26 rests upon the stationary blade 23 and is provided with cutting teeth 27 similar to the teeth 25. The movable blade has a slot 28 provided longitudinally of its medial portion with shoulders 29 in opposed spaced relation in the lower part of said slot. A slide member 30 is slidably positioned within the slot 28 and rests upon the shoulders 29 and a screw 31 is provided with its head resting within said slide member and its lower portion threaded into the central portion of the stationary blade 23 and terminating above the lower face of said stationary blade. A pair of upstanding guide lugs 32 are formed on the upper side of the stationary blade to co-operate with slots 33 in the under face of the movable blade. It will be noted that the stationary blade has a relatively wide depressed area 23a to provide sliding bearing surfaces for the movable blade at its front and rear edges.

The movable arm 19 is extended beyond the shoulder 18 to form a vertically positioned sleeve-like bearing 34 and extending forwardly and downwardly beyond said sleeve-like bearing is a movable blade operating finger 35 adapted to engage the notch 36 formed centrally of the rear edge of said movable blade.

A slightly resilient cap plate 37 is formed integrally with the stationary handle 15 just above the cylindrical housing 16. This cap plate, at its lower forward edge, engages a smooth upper surface of the movable blade 26. A vertical bolt 38

member 38, provided with an integral wing head 39, extends downwardly through the cap plate 37, the sleeve-like bearing 34, the upper portions of the extension 20 and through an aperture 5 in the rearwardly extending portion 24 of the stationary blade. It will be noted in Fig. 3 that that portion of the bolt extending into the extension 20 is threaded therein, and that there is a smaller smooth surfaced end on the bolt 38 10 which fits into the aperture in the stationary blade. It will also be noted that this bolt 38 does not extend through to the under face of the extension 20 which is flush with the under face of the stationary blade 23. Thus it will be seen 15 that there are no screw or bolt holes in the bottom face of the stationary blade 23 or in the under face of the lateral extension of the cylindrical housing 16 which can catch the ends of hairs and pull them. Attention is also called to 20 the downwardly and backwardly extending lower edge of the cylindrical housing extension 20 and the edge of similar shape at the lower rear portion of the stationary blade. Because of the slant given to this joint, it is impossible for any 25 hairs to be caught therein.

When it is desired to remove the blade members 23 and 26, it is only necessary to unscrew the bolt 38 until its lower extended portion has been withdrawn from engagement with the extension 24 on the stationary blade. The two blades may then be removed as a unit for sterilizing, and if it is desired to sharpen the blades, after they have been removed from the clippers, the small bolt 31 may be removed and the two 35 blades will fall apart.

In the modification shown in Figs. 8 through 14, I have provided a construction in which the stationary blade 40 forms the entire lower face of the clippers, and, as in the embodiment above 40 described, the under face of this blade is also characterized by a surface unbroken by any apertures or joints of any kind.

In Figs. 8 and 9, instead of manual operating handles or supporting arms, I have shown generally a rectangular bracket member or supporting arm 41 of a type which is generally utilized in power driven clippers. The lower end of this supporting arm is bent downwardly and then outwardly in a horizontal position, as shown at 45 42, and is provided with an aperture positioned centrally of said horizontal portion and another pair of apertures toward the ends of said horizontal portion. This horizontal portion is adapted to slide beneath the upstanding retaining member 43 formed on the rear of the upper 50 side of the stationary blade 40.

The movable blade 44 rests upon the stationary blade and is provided at its rear edge with a downward extension 45 adapted to ride in the 60 channel 46 formed in the upper face of the stationary blade. To properly tension the movable blade relative to the stationary blade a substantially U-shaped spring member 47 is provided and is secured to the upstanding retaining member 43 by bolts 48 which extend through said retaining member and through the horizontal portion of the supporting arm 41 terminating in threaded engagement with the stationary blade 49 above the lower face of said blade. The spring 65 70 75 47 is arched slightly, as shown best in Fig. 9, and its forward edge 49 is turned downwardly to engage the transverse groove 50 in the upper face of the movable blade.

The rear portion of the movable blade 44 has a centrally positioned notch 51 formed therein

which is adapted to engage a suitable reciprocating operating lever. In Figs. 8 and 9 the operating lever, not shown, will be driven by a suitable source of power, such as an electric motor.

In Fig. 14, is shown the same structure as applied to hand operated clippers. A stationary arm 52 is provided with a cylindrical housing 53 carrying a portion of a movable arm 54 which has a vertically positioned bearing member 55 and downturned movable blade operating portion 56, as shown and described in the embodiment in Figs. 2 and 3. In this instance, however, it is preferable to form the cap plate 57 separate from the stationary arm 52, so that the blades 40 and 44 may be more easily removed. A vertical bolt member 58, similar to the bolt 38, in Figs. 2 and 3, extends through said cap plate, vertical bearing 55, the upstanding portion 43 at the rear of the stationary blade, the central aperture in the horizontal extension 59 formed integral with the housing 53 and is threaded into the rear portion of the stationary blade 40 terminating above the lower face of said blade.

From the foregoing description, it will be seen that I have provided an improved construction 25 for hair clippers wherein the removal of the two cutting blades is an extremely simple operation which requires very little time. In addition, I have provided a construction wherein the under face of the stationary blade is free of any bolt 30 holes or crevices which might catch and pull the hair.

I have also provided one form of construction 35 wherein the cap plate is formed integral with the stationary cutting arm, thus reducing the number of separate parts.

In that construction which relates to a type adaptable for either power driven or manually operated clippers, I have provided an arrangement whereby the cutting blades and tensioning 40 spring may be removed as a unit.

In connection with those views showing the supporting arm 41 adaptable for use with power driven clippers, the supporting arm may be formed substantially at right angles to the blade 45 structure and the lower face of the stationary blade may be given a convex shape. This variation is suggested to adapt the clippers for use by the operator in clipping his own hair, and the device may be used with much of the same motion 50 as a conventional safety razor.

It will, of course, be understood that various changes may be made in the form, details, proportions and arrangement of the parts without departing from the scope of my invention, which, 55 generally stated, consists in a device capable of carrying out the objects above set forth, and in the novel parts and combinations of parts disclosed and defined in the claims.

What is claimed is:

1. A hair clipping device comprising a blade supporting element, a blade assembly comprising a pair of blades slidably and detachably interconnected as a unit, said supporting element and one of said blades being provided with a tongue 65 and slot connection lying in a horizontal plane and being of substantial width and a retaining element extending through said tongue and slot connection to rigidly anchor the blade unit to said supporting element.

2. A hair clipping device comprising a blade supporting element having a horizontally positioned slot extending inwardly throughout its edge and said element also having an aperture extending vertically through said slotted portion. 70 75 75

5 a pair of slidable blades detachably interconnected as a unit, one of said blades including a horizontally positioned tongue element extending outwardly from the rear edge of said blade and adapted to fit in said slotted portion of said supporting element, said tongue having an aperture therethrough in alignment with the aperture through said slotted portion, and a retaining element extending through the aperture in said 10 slotted portion and said tongue.

10 3. A hair clipping device comprising a blade supporting element, a pair of blades slidably interconnected as a detachable unit, a blade operating lever, one of said blades having an operating connection with said operating lever, said supporting element and one of said blades being provided with a tongue and slot connection, and a combined pivot pin and retaining element extending through said blade operating lever and 15 20 said tongue and slot connection to secure the

operating lever supporting element and blade assembly together.

4. A hair clipping device comprising a blade supporting element having a horizontally positioned tongue extending outwardly from an end 5 thereof, a pair of relatively slidable blades detachably connected together as a unit, one of said blades having a horizontally positioned slot extending inwardly from an edge thereof and co-extensive with a major portion of said edge, said 10 blade also having an aperture extending vertically through said slotted portion, said tongue being adapted to fit the slot in said blade and having an aperture therethrough in alignment with the aperture through said slotted portion, 15 and a removable retaining element extending through the aperture in the slotted portion of said blade and through said tongue.
